UNITED STATES PATENT OFFICE.

ANTON AUGUST HAAHR, OF COPENHAGEN, DENMARK, ASSIGNOR TO UNITED SHOE MACHINERY COMPANY, OF PATERSON, NEW JERSEY, A CORPORATION OF NEW JERSEY.

WELT-SLASHING ATTACHMENT FOR WELT-SHOE-SEWING MACHINES.

1,194,621.

Specification of Letters Patent. Patented Aug. 15, 1916.

Application filed July 1, 1915. Serial No. 37,464.

To all whom it may concern:

Be it known that I, ANTON AUGUST HAAHR, a subject of the King of Denmark, residing at Copenhagen, F., Denmark, have 5 invented certain new and useful Improvements in Welt-Slapping Attachments for Welt-Shoe-Sewing Machines; and I do hereby declare the following to be a full, clear, and exact description of the invention, such 10 as will enable others skilled in the art to which it appertains to make and use the same.

The present invention relates to an improvement in welt slashing attachments for 15 welt shoe sewing machines.

The object of the invention is to improve the construction and mode of operation of welt slashing attachments, and to this end the invention consists in the mechanism 20 hereinafter described and particularly pointed out in the appended claims.

In the accompanying drawings illustrating the preferred form of the invention, Figure 1 is a side elevation of the upper 25 part of so much of a welt shoe sewing machine as is necessary to show the application of the improved welt slashing attachment thereto; Fig. 2 is a perspective view of the lower part of the machine shown in 30 Fig. 1; Fig. 3 is a side elevation of the improved welt slashing attachment on an enlarged scale; Fig. 4 is a front elevation of the parts shown in Fig. 3, partly in section; Fig. 5 is a plan of the toe of a shoe, the welt 35 guide and welt slashing knife, showing the relative positions thereof during the welt slashing operation; Fig. 6 is a side elevation of the welt after the slashing operation, and Fig. 7 is a cross-section of the welt through 40 one of the cuts.

The welt shoe sewing machine illustrated in connection with the preferred embodiment of the improved welt slashing attachment, is substantially the same as the machine 45 illustrated and described in the patent to Eppler No. 1,108,560, dated August 25, 1914, and consists of a curved, hooked needle 1, a thread finger 2, a looper 3, a work rest 4, a welt guide 5, a take-up device 6, and other 50 parts not essential to the disclosure of the present invention. These parts, together with their actuating mechanism, are con-

structed and arranged to operate in substantially the same manner as the corresponding parts of the machine of the patent above 55 referred to.

The welt slashing attachment is adapted to form a series of transverse, obliquely disposed cuts in the under side of the welt at certain requisite times during the operation 60 of the stitch forming devices. The welt slashing operation is performed immediately after the welt guide has come to rest at the end of its forward movement and while it is pressing the welt against the shoe. The 65 welt slashing is performed by a welt slashing knife 8 mounted in a frame 10 projecting rearwardly from the welt guide 5, the knife 8 being actuated through suitable connections by a cam 12 mounted on the main 70 shaft of the machine. The cam 12 rotates in timed relation with the other parts of the sewing machine so as to cause the slashing knife 8, at the requisite times, to form a transverse cut in the welt at each operation 75 of the stitch forming devices. The knife 8 is provided with a round shank received in a split nut 14, the arrangement being such that the length, depth, and angular relation 80 of the cut to the welt may be regulated and adjusted. The welt slashing knife 8 is clamped in adjusted position in the nut 14 by means of the screw 16. The nut 14 is secured to a slide 18, which is received in the frame 10 and is adapted to reciprocate there- 85 in. The reciprocatory motion is imparted to the slide 18 by means of a slotted arm 20 of a bell crank lever 22 secured to the shaft 24, mounted in suitable bearings on the frame of the machine. The slot 26 of the 90 arm 20 engages a pin and roll 28 projecting laterally from the slide 18. The other arm 30 of the bell crank lever 22 is provided with a slot which receives the pin 32 of a lower toggle arm 34. The upper toggle arm 95 36 is pivotally connected to an arm 38 of a bell crank lever 40 pivotally supported upon the frame of the machine. The other arm 42 of the bell crank lever 40 is provided with a pin and roll adapted to travel in the cam 100 slot 44 of the cam 12. The toggle arms 34 and 36 are connected by means of a toggle pin 46 received in an angular slot in the forward end of a controlling lever 48 pivotally

mounted at 50 upon the frame of the machine. The angular movement of the controlling lever is limited by a stop pin 52. A spring 54, one end of which engages the under side of the controlling lever 48, and the other end of which engages the frame of the machine, tends to maintain the lever 48 in raised position, as shown in Figs. 1 and 3. The angular slot in the forward end of the controlling lever 48 is composed of a toggle-breaking slot 56 and a toggle-straightening slot 58 which, when the lever 48 is in lowered position, are respectively substantially horizontal and vertical. When the controlling lever is in raised position as shown in Figs. 1 and 3, the toggle pin 46 is adapted to reciprocate in the horizontal or toggle-breaking slot 56, and at such time the movement imparted to the bell crank lever 40 by the active part 60 of the cam 12 is not communicated to the welt slashing knife 8 which, therefore, remains inoperative. When, however, the controlling lever is lowered so as to bring the toggle pin 46 within the vertical or toggle-straightening slot 58, the toggle arms 34 and 36 act as one link, and the movements imparted to the bell crank lever 40 by the active part 60 of the cam 12, operate to turn the bell crank lever 22 in its bearings, thereby causing the welt slashing knife 8 to be reciprocated to form the series of transverse cuts in the welt during the stitch forming operation.

When it is desired to form the cuts in the under side of the welt during the stitch forming operation, as for instance when sewing around the toe of the shoe, the controlling lever 48 is lowered. The lowering of the controlling lever is within the control of the operator and is effected by means of a rod 62, the upper end of which is connected to the controlling lever, the lower end of the rod being attached to the outer end of an arm 64 secured to one end of a shaft 66, rotatively mounted in a bracket 68 secured to the frame of the machine. An arm 70 secured to the other end of the shaft 66 is connected with a bell crank lever 72 by means of a link 74. The bell crank lever 72 is pivotally supported on a depending arm 76 from the bracket 68. To the lower end of the arm 78 of the lever 72 is secured a knee-plate 80. When the operator presses his knee against the knee-plate, the bell crank lever 72 is caused to oscillate on its pivot. This oscillation of the lever 72 swings the arm 70, thereby rotating the shaft 66, depressing the outer end of the arm 64 to which is secured the rod 62, and bringing the controlling lever 48 into its lowered position. It will be observed that the welt slashing knife has a movement relative to and independent of the welt guide, so that, during such times as the welt slashing mechanism is inoperative, the welt guide moves

toward and from the shoe without imparting any movement to the welt slashing knife.

The nature and scope of the present invention having been indicated, and the preferred form thereof having been specifically described, what is claimed is:

1. A welt shoe sewing machine having, in combination, stitch forming devices, a welt guide, means for moving the welt guide toward and from the shoe during the stitch forming operation, and a welt slashing knife mounted on the welt guide for forming a series of transverse cuts in the under side of the welt. 70 75

2. A welt shoe sewing machine having, in combination, stitch forming devices, a welt guide, means for moving the welt guide toward and from the shoe, a welt slashing knife mounted on the welt guide, and means 80 85 for moving the welt slashing knife relatively to the welt guide.

3. A welt shoe sewing machine having, in combination, stitch forming devices, a welt guide, means for moving the welt guide toward and from the shoe, a welt slashing knife under the control of the operator and acting when thrown into operation to form a series of cuts in the under side of the welt during the stitch forming operation, and 90 95 means for preventing movement of the welt slashing knife, except when thrown into operation by the operator.

4. A welt shoe sewing machine having, in combination, stitch forming devices, a welt 100 guide movable toward and from the shoe, a welt slashing knife for forming a series of transverse cuts in the under side of the welt, and means for actuating the welt slashing knife to cut a slash in the welt independently of the movement of the welt guide, and means for throwing the knife into and out of operation. 105

5. A welt shoe sewing machine having, in combination, stitch forming devices, a welt 110 guide, a welt slashing knife, a cam for actuating the welt slashing knife, connections between the cam and the welt slashing knife, including a toggle, and a controlling lever having a toggle-breaking slot and a 115 toggle-straightening slot.

6. A welt shoe sewing machine having, in combination, stitch forming devices, a welt 120 guide movable toward and from the shoe, a welt slashing knife for forming a series of transverse cuts in the under side of the welt, mounted on the welt guide, and means for adjusting the position of the welt slashing knife so as to vary the length and depth of the cuts. 125

7. A welt shoe sewing machine having, in combination, stitch forming devices, a welt guide movable toward and from the shoe, a welt slashing knife for forming a series of transverse cuts in the under side of the welt, 130

a cam and suitable connections for actuating the welt slashing knife while the welt guide is stationary, and means under the control of the operator for rendering said 5 connections operative and inoperative.

8. A welt shoe sewing machine having, in combination, stitch forming devices, a welt guide, means for moving the welt guide toward and from the shoe during the stitch

forming operation, a welt slashing knife 10 mounted on the welt guide for forming a series of transverse cuts in the under side of the welt, mechanism for actuating the knife to form a cut in the welt independently of the movement of the welt guide, and means 15 for throwing the knife into and out of operation.

ANTON AUGUST HAAHR.
